UNITED STATES PATENT OFFICE.

ALPHEUS FAY, OF LOUISVILLE, KENTUCKY.

AERATING BUTTER-SEPARATOR.

1,032,663.

Specification of Letters Patent. Patented July 16, 1912.

Application filed February 19, 1912. Serial No. 678,576.

To all whom it may concern:

Be it known that I, ALPHEUS FAY, a citizen of the United States, and a resident of Louisville, in the county of Jefferson and State of Kentucky, have invented a certain new and useful Aerating Butter-Separator, of which the following is a specification.

The object of my invention is to provide improved means for the performance of such processes in connection with the treatment of cream, milk or butter as requires either mechanical agitation or aeration or both.

The processes to which my invention is most applicable will hereinafter be more fully described.

My object also is to simplify the construction of apparatus of this character, and to add to its efficiency and durability.

My invention consists in the details of construction and arrangement, as will hereinafter be more fully described and claimed.

In the drawing: Figure 1 is a perspective view of a device embodying my invention, parts of the vessels being represented as broken away. Fig. 2 is a vertical sectional view of the agitator and its shaft. Fig. 3 is a sectional detail of part of the bracket.

In my present invention, the device is characterized by the combination of a rotated agitator and a stationary brake to co-act therewith. The agitator 1 is of such design as to produce centrifugal impelling effect on the liquid, and is mounted on a shaft 2, journaled and supported in a bracket 3, mounted to extend over the open top of the vessel 4, in a suitable manner, to be later described. The transverse shaft 5, journaled in the bracket 3, has the bevel gear 5^a and the agitator shaft 2 has a bevel pinion 2^a meshing with the gear 5^a. Preferably, as shown, the transverse shaft 5 extends over the upper end of the agitator shaft 2 and carries its gear 5^a outside the pinion 2^a. This constitutes the larger bevel gear a shield against entanglement of any object between the gear and pinion where they mesh, thus adding to the safety of operation of the device.

The bracket 3 comprises the main supporting hub 3^a, with an upward extension carrying the bearing 5' of the shaft 5, and with transverse members 3^b and 3^c, above and below the shaft 5, respectively, extending over to the other bearing 5'' of said shaft 5. The lower member 3^c has a socket 3^d, and a detachable sub-bracket 2^b, for the agitator shaft 2, below the pinion 2^a, has a shank 2^b

entering this socket 3^d upwardly. The socket and shank are of circular cross-section, but the bracket 3 has a straight shoulder 3^d' below and at one side of the socket 3^d, while the sub-bracket 2^b has a straight side 2^b'' that engages accurately with the straight shoulder when the shank enters the socket. This prevents turning of the sub-bracket. 60 A set screw 2^c enters the socket 3^d and engages with a depression in the shank, as shown in Fig. 3. Preferably, the screw and the socket are so positioned, relatively, that tightening of the screw will draw the sub-bracket up tight to the bracket, by wedging action of the screw-point on the inclined sides of the depression. By the above means, a firm but detachable bearing is afforded for the agitator shaft 2, below its pinion 2^a. An 70 upper bearing 2^d is provided for the upper end of the agitator shaft, in the part of the bracket 3 below the bearing 5'' of the shaft 5.

By having the lower bearing 2^b detachable from the bracket, it is possible to press the pinion 2^a tightly on the shaft 2 before it is put into the machine, as is necessary to avoid loosening of this pinion in service, as has been the fault of machines where such a pinion must be pinned or fastened by set 80 screw on its shaft. The gear 5^a may be pressed tightly onto its shaft 5, and the handle 6, which is used for manually operating the machine, may be suitably secured on the shaft after assemblage. 85

The vessel 4 is supported on a base 3^e, which has a standard 3^f at one side, with a head 3^g having a socket to receive a shank 3^a' of the bracket 3, extending down from the hub 3^a thereof. Offsets 3^g' and 3^a'' on the head 3^g and hub 3^a, respectively, engage to prevent turning of the bracket on the standard when they are assembled. The head 3^g has ears 3^g'' at one side, adjacent to each other, and a slit takes into the socket of the head, splitting this side of the head. A screw 3^g''' takes through the ears 3^g'' and draws them together, so that the head is made to contract on the shank 3^a' and thus hold the bracket rigidly on the standard. 95 The upper member 3^b of the bracket 3 affords a rest for the hand, to hold the entire device stationary when it is operated by turning the crank 6. 100

The vessel 4 has a cock or faucet 4^a at one side, at its bottom, to withdraw liquid from the vessel. As this apparatus generally is used in a process where some solid substance is granulated or otherwise comminuted, it is 110

necessary, to best facilitate the operations, to provide a means for readily withdrawing the liquids but to retain the solid particles. With this end in view, I provide an 5 inner vessel 4^b, fitting closely within the vessel 4, and having a perforated bottom 4^b. Handles 4^b on this vessel 4^b enable the operator to withdraw the inner vessel with the solid substance, after which the liquid 10 may be drained from the vessel through the faucet 4^a. If desired, said faucet may be dispensed with, if found convenient to remove the vessel 4 from the machine, and pour the liquid from it. This may be expedient if the apparatus is of small size.

15 The brakes 7 and 7^a that co-act with the agitator 1 are each composed of an upright strip, preferably of wood, lying against the sides of the inner vessel 4^b. The brake 7 extends up into a socket 7' in the lower side of the lower member 3^c of the bracket 3, and a set screw 7'' holds it therein. The lower end of this brake 7 bears firmly on the bottom of the vessel 4^b, and thus holds the 20 vessel against turning within the vessel 4, as it may otherwise do, under the influence of the motion of the liquid in the vessels. The other brake 7^a also bears firmly against the bottom of the vessel 4^b, for the same 25 purpose, and is secured to the vessels by a clip 7^a' taking over the rim of the vessel. This clip is of U-shaped formation to embrace the cross-section of the brake-strip, with each member of such formation bent 30 down to engage over the rim, and may be conveniently formed of wire. Each brake strip is narrower throughout its middle region, with wider end parts, above and below, so that such middle regions lie away from 35 the sides of the vessel. Also, these middle regions are perforated. Thus, the spaces between these regions and the vessel sides, and these perforations, afford an added agitating effect on the liquid impelled against the 40 brakes by the agitators. It will be understood that the entire bottom and sides of the inner vessel 4^b may be perforated, if desired, but usually perforation of the bottom only, as shown, is sufficient, as well as more 45 economical.

50 The agitator 1 comprises the tubular shaft 1^a and upper member 1', integrally formed, as here shown, and a lower member 1'' attached to the member 1'. The tubular shaft 55 is provided with a hub 1^a', also preferably integral with it, and joining it by arms 1^a''', so that the upper end of said tubular shaft is left open for the admission of air. The hub 1^a' has juxtaposed ears 1^a'' at one 60 side, and a slit into its central opening divides that side, with the ears on opposite sides of the division. A screw 1^a''' takes through the ears, and contracts the hub on the shaft 2, so that the agitator will rotate 65 with the shaft, and is supported thereby,

but may, by loosening this screw, be adjusted up or down on the shaft 2, to accommodate the apparatus to different quantities of material to be operated upon. The bracket 3 is positioned high enough above the upper 70 rim of the vessel to allow the vessel to be nearly filled with liquid, without the upper open end of the tubular shaft 1^a being submerged, if adjusted to its highest position, i. e., with the upper end of the hub 1^a 75 against the lower side of the bearing or sub-bracket 2^b.

Each member 1' or 1'' of the agitator 1 comprises a plane body part 1^b' or 1^b'', respectively, that of the upper one having bosses 1^c' on its periphery, while the lower one has upturned sides 1^c'' that surround the upper plane body part and have screws 1^c'' taking into the bosses 1^c' through vertical slots 1^c'' in said 80 sides. This allows upward and downward adjustment of the lower member on the upper member, to be clamped in any desired adjustment by said screws. The sides 1^c'' have a series of openings 1^c''', distributed around the member, these openings being of somewhat elongated hexagonal shape, with angles presented longitudinally 85 around the agitator. As shown, and as I prefer to form this agitator, it is circular, or 90 cylindrical. The upper member has a free, unobstructed opening from the interior of the tubular shaft 1^b, around the shaft 2, to allow ready circulation of air, from the open upper end of the tubular shaft down into the 95 hollow interior of the agitator, but the lower member fits snugly around the shaft, and thereby serves to support the agitator at its lower end, to maintain it concentric with its 100 shaft. The parts may be conveniently cast, 105 of aluminum, the upper member and its tubular shaft and the hub 1^b therefor being integral, and the cupped lower member with its slotted and apertured sides being in a single piece. Preferably, the inner lower 110 side of the upper member and the inner upper side of the lower member are concave to a slight extent, produced by dishing said members in their plane body parts.

I have found by experience that, although 115 the sides of this agitator are cylindrical, and the agitator is rotated on the axis of this cylinder, the impelling effect produced by the friction of the liquid with the parts of the agitator thus rotated, and the engagement of the edges of the openings 1^c''', is ample for the purposes of my improved apparatus, under most conditions. Under 120 this effect, a centrifugal action results, forcing the liquid away from the exteriors of said sides, and from the hollow interior of the agitator. Thus, a partial vacuum is produced in said hollow interior, and a flow 125 of air is induced down through the tubular shaft, by atmospheric pressure, into the hol- 130

low interior. This air, mixing with the liquid, will be carried out into the main body of liquid in the vessel, and a circulation of liquid and air will thus be set up in the liquid, amounting to a combined aerating and mechanical agitation. The brakes 7 compel this action by preventing the whirling of the main body of liquid, and by breaking up the air currents, through the spaces and perforations before described. It is desirable that this breaking-up of the currents be distributed into such various orifices as these spaces and perforations afford, so that there is thorough collision of the liquid particles, and of the air particles with the liquid particles. The consequence of the operation is that the entire contents of the vessel are brought into a state of ebullition, or bubbling, resembling the appearance of boiling, although of course no such temperature is ever used in butter-treating processes, as boiling temperature is well known to be injurious to all milk products. It is by the utilization of the effects of boiling or ebullition, in a mechanical way, without entailing the injurious effects of heat, that some of the more important results of the processes to be described are reached. By adjusting the lower member from the upper one, the effect 30 of the agitator may be varied to suit the use to which the apparatus is applied.

As above described, the impelling effect is produced by the surface and peripheral part of the agitators only, leaving the interior thereof smooth and unobstructed; also that the openings in the sides, being polygonal, cause a congestion of the outward flow of the liquid and air from the interior, in the region of a plane surrounding the middle region, between the upper and lower plane body parts, due to the greater outflow from the widened parts of the openings. Also, the concavity of the interiors of the plane body parts conduces to this effect. This results in a more intimate intermingling of the liquid and air particles, adding to the completeness of the aeration while allowing undiminished mechanical agitation by the upper and lower widened regions of the 50 sides of the agitator between the openings.

For churning, sweet or sour cream, or sweet or sour whole milk, is placed in the vessel 4, with the vessel 4^b in place, if used, the agitator being adjusted, as before described, to bring its impeller members about midway of the depth of the body of liquid. If cream is used, its temperature may be from 60 to 65 degrees Fahrenheit, while if whole milk is used, the temperature should 55 be somewhat higher, or from 65 to 70 degrees Fahrenheit. The churning agitation and aeration is then kept up for a period of from three to five minutes, when the butter will have become thoroughly separated from 65 the cream or milk, by ebullition taking place

in the liquid. The butter will now be ready for washing, and will be distinct from the residue, in small solid particles, and the residue will be in a uniformly liquid state. If whole milk has been used, the residue will 70 contain all the milk solids except the butter, and if the milk was sweet, this residue will be sweet and palatable. The inner vessel 4^b is now raised and placed on the rim of the outer vessel 4, in tilted position, so that the 75 residue is completely drained from this inner vessel, and then is withdrawn from the outer vessel through the faucet 4^a. The vessel 4^b, with the butter particles therein, is now replaced in the outer vessel 4, and the 80 bracket and agitators, which, were, of course, removed before raising the vessel 4^b, are again placed in operative position. A suitable quantity of pure water is now added, preferably at a temperature of from 85 50 to 55 degrees Fahrenheit. The butter particles are now agitated and aerated in this body of cool water, increasing the thoroughness of separation of the residue. This body of water, contaminated by the residue thus 90 separated, is drawn off, with the inner vessel raised as above described. The butter will now have reached a granulated condition, the granules approximating the granules of sugar, as ordinarily seen on the market. 95

The butter is now ready for salting, preparatory to working the butter into the solid consistency that it is to have for use. For salting the butter, a solution of a pint of salt to a gallon of water is applied to the butter granules in the vessel 4^b, which has again been lowered in the vessel 4. The temperature of this solution should be from 100 50 to 55 degrees Fahrenheit. The agitator is again applied, and the agitation and aeration resumed, preferably at reduced speed, for about 30 to 60 seconds, bringing salt particles into intimate relation with every particle of the granular butter. On completion of this operation, the vessel 2^b may be again raised and the salt solution withdrawn. The butter mass may be drained of 105 all solution except that which has been incorporated with the mass, which, now thoroughly salted, with great homogeneity, is taken from the vessel and worked or pressed to the proper useful consistency. The washing water and the salt solution were used at 110 low temperatures as described to maintain a desirable hardness of the butter granules throughout the operations, which results in a finished product of the finest texture, after final working or pressing. All of the parts being readily disassembled, and being of open 115 formation, cleansing of the apparatus is now done with ease. The brakes 7 and 7^a, are easily removable from the vessels, for raising the vessel 4^b, or for cleaning, the former being removed along with the bracket and 120 125 130

agitator, while the latter is readily detached and attached to the vessel-side, by means of its clip.

It may be noted that, in churning sour milk, and for other operations for which it may be desired to use my apparatus, a reduced amount of aeration is often desirable, or it may be desirable to entirely eliminate the aeration, and apply mechanical agitation, 10 with the accompanying centrifugal action producing liquid currents only, instead of the combined air and liquid currents. To provide for this, there must be a means of decreasing the aeration without diminishing 15 the agitating effect. The adjustment of the lower member 1" upward on the upper member 1' effects this change, since the polygonal openings, in the sides of the agitator, will be effective for air emission only in 20 those parts of their areas below the plane body part 1^b of the upper member. The parts of the sides adjusted above this plane body part 1^b will act centrifugally, as before, so that the mechanical agitation will 25 be unaltered. It would not be sufficient to simply decrease the inflow of atmospheric air to the hollow agitator, while its hollow interior had its volume unaltered, since this would tend to increase the resistance of the 30 apparatus, requiring greater effort in turning, unnecessarily. Ease of operation is one of the chief objects of my invention, and the perfect adaptation of the operative parts to special conditions tends to insure this at all 35 times. It will be seen that if the lower agitator member is adjusted to its highest position, bringing the plane body parts together, the aeration will be practically eliminated, only being of such extent as resulted 40 from inlet of air through the slight apertures left between the parts of the agitator. As will be noted in Figs. 1 and 2, the lower sides of the openings are flush with the inner, upper surface of the plane body part 45 of the lower agitator member 1". This permits uninterrupted exit of air and liquid from the agitator, and avoids the collection of butter or other solid particles within the hollow interior thereof.

50 I have set forth the above churning process to illustrate the use of my apparatus, and it will be understood that other advantageous uses will be suggested in the employment of my invention, and divers minor 55 modifications may occur in such adaptation. Therefore, I do not wish to be understood as limiting myself to the precise details herein described, but

What I claim as new and desire to secure 60 by Letters Patent is:

1. In a device of the character described, an agitator comprising a shell uniformly cylindrical interiorly and exteriorly, closed at top and bottom, except through an atmospheric air inlet in its top, and having

openings in its convex sides, for the outlet of air, the hollow interior of said shell being free and unobstructed.

2. In a device of the character described, an agitator comprising a shell uniformly cylindrical interiorly and exteriorly, closed at its top and bottom, except through an atmospheric inlet in its top, and having openings in its convex sides, for the outlet of air, said openings being of hexagonal formation. 75

3. In a device of the character described, an agitator comprising a shell uniformly cylindrical interiorly and exteriorly, closed at its top and bottom, except through an atmospheric inlet in its top, having openings in its convex sides, for the outlet of air, said openings being of hexagonal formation with wider parts alined medianly of said convex sides between top and bottom 85 thereof.

4. In a device of the character described, an agitator comprising a shell uniformly cylindrical interiorly and exteriorly, closed at its top and bottom, except through an atmospheric inlet in its top, having openings in its convex sides, for the outlet of liquid and air, said openings being of hexagonal formation with wider parts alined medianly of said convex sides between top and bottom 95 thereof, and said top and bottom of the shell being concave inside the hollow interior of the shell to medianly congest the outflow of liquid and air, substantially as and for the purposes specified. 100

5. In a device of the character described, an agitator comprising a disk-shaped member and a cup-shaped member uniformly cylindrical interiorly and exteriorly, embracing the disk-shaped member, said cup-shaped member having openings in its convex sides, and having slots in said sides, and fastening means through said slots to said disk-shaped member, to secure the cup-shaped member in adjusted positions on the 105 disk-shaped member, and one of said members having an air inlet through it, said openings in the sides of the cup-shaped member being air outlets. 110

6. In a device of the character described, 115 an agitator comprising a disk-shaped member and a cup-shaped member embracing the disk-shaped member, said cup-shaped member uniformly cylindrical interiorly and exteriorly, having openings in its convex sides and being adjustable with respect to the other member, a tubular shaft attached to one of said members centrally thereof, with its interior communicating with the space between said members and 120 with its upper end open, and a hub and arms attaching said hub to said upper end. 125

7. In a device of the character described, the combination of a vessel, a brake in the vessel, and a hollow agitator uniformly cy- 130

cylindrical interiorly and exteriorly, with openings in its convex sides and an air inlet to its top, the hollow interior of said shell being free and unobstructed, and means for 5 rotating said agitator.

8. In a device of the character described, an outer vessel, an inner perforated vessel, agitating means in the vessels free from engagement therewith, a bracket supporting 10 the agitating means, and a brake to cooperate with the agitating means, attached to the bracket and bearing against said inner vessel.

9. In a device of the character described, an impelling member capable of rotation 15 and presenting edges only in direction of rotation, and presenting unobstructed surfaces otherwise, whereby said surfaces act frictionally, without impact, on liquid in which they may be immersed, to impel it 20 centrifugally.
